UNITED STATES PATENT OFFICE.

FRED LUNDBERG, OF CHICAGO, ILLINOIS.

LOCK FOR BURIAL-CASKETS.

1,345,451.

Specification of Letters Patent.

Patented July 6, 1920.

Application filed December 28, 1917. Serial No. 209,276.

To all whom it may concern:

Be it known that I, FRED LUNDBERG, a citizen of the United States, and a resident of the city of Chicago, county of Cook, and State of Illinois, have invented certain new and useful Improvements in Locks for Burial-Caskets, of which the following is a specification.

My invention relates to improvements in burial caskets of the type in which the upper portion thereof is formed of a plurality of swinging wall parts or moldings.

The object of my invention is the production of a lock whereby said movable wall portions or molding members of a casket, will be automatically locked when swung to closed positions, and which lock will permit of ready manipulation to unlock said wall portions or molding members.

20 A further object is the production of a lock as mentioned which will be of durable and economical construction and efficient in use.

Other objects will appear hereinafter.

25 The invention consists in the combinations and arrangements of parts hereinafter described and claimed.

The invention will be best understood by reference to the accompanying drawings, 30 forming a part of this specification, and in which,

Figure 1 is a side elevation of a burial casket embodying the invention,

Fig. 2, a top plan view of the casket with 35 the top panel thereof removed,

Fig. 3, a partially sectional enlarged view of one corner of the casket, as seen in Fig. 2, and

40 Figs. 4 and 5, sections taken on lines 4—4 and 5—5 respectively of Fig. 3.

The preferred form of construction as illustrated in the drawings is shown applied to a casket comprising a lower body portion or casket proper 6, and wall or molding members 7 swingingly secured to the upper edge of the casket body 6 by hinges 8. When the members 7 are in closed position, the same are adapted to support a panel 9 which closes the opening in the upper side 45 of the casket, as will be readily understood. The members 7, however, are mounted to permit of outward swinging of the same to positions as seen in dotted lines in Figs. 4 and 5 when the panel is removed, in order 50 to permit of ready access being gained to the interior of the casket in placing the

body therein or to permit of a full view of the corpse, if desired, when the casket is in use.

The subject-matter of this application is 60 embodied in a lock for locking adjacent ends of the wall members 7 together when said members are in closed position. The lock, of which there will be a number used in each casket, comprises a lug 9', the base 65 portion 10 of which is rigidly fastened as by rivets or other suitable fastening devices 11 to one of the wall members 7. Upon the other wall member is provided a plate 12 suitably fastened as by rivets or other se- 70 curing devices 13, said plate 12 being pro- 75 vided at one end with an inwardly and up- wardly extending ear or flange 14, which results in the formation of an upwardly opening socket 15 which is adapted, when 80 the wall members are in closed position, to snugly receive the lug 9', as clearly seen in Figs. 3 and 5. Provided upon plate 12 is a resilient arm 16 in the form of a leaf spring, 85 one end of which is secured by lugs or back- turned fingers 17 to said plate 12. The op- 90 posite end of arm 16 carries a stud 18 which normally projects through an opening 19 formed in flange 14 into one side of socket 15. Formed in the lug 9' is a slot or open- 95 ing 20 also adapted for engagement by the stud 18, as clearly seen in Fig. 3, the ar- 100 rangement being such that when said stud is in engagement with slot 20, the wall mem- bers 7 will be locked together. The termi- 105 nals of the lug 9' and stud 18 are beveled, as seen, so that when the wall members 7 are swung to closed position, in which case the lug 9' will be carried into engagement with the socket 15, stud 18 will be automatic- 110 ally pressed back until slot 20 registers therewith, whereupon said stud will auto- matically move into engagement with said slot and thus effect automatically the lock- ing of said wall members together, when 100 swung to closed position.

Formed upon the free end of arm 16 is a depending finger piece 21 through the me- dium of which said arm may be readily flexed inwardly by the fingers to effect man- ual retraction of stud 18 when it is desired to unlock wall members 7. The arrange- 105 ment is extremely simple, while at the same time the same is highly efficient for the pur- pose.

While I have illustrated and described the preferred form of construction for carrying

my invention into effect, this is capable of variation and modification without departing from the spirit of the invention. I, therefore, do not wish to be limited to the 5 precise details of construction set forth, but desire to avail myself of such variations and modifications as come within the scope of the appended claims.

Having described my invention what I 10 claim as new and desire to secure by Letters Patent is:

1. In a burial casket provided with hinged wall portions disposed at right angles to each other, means for locking said wall portions in closed relation with each other, comprising a slotted lug projecting perpendicularly from one edge of one of said wall portions; a socket on the other wall portion adapted to snugly receive said lug when said wall portions are in closed positions; and a rearwardly yieldable stud projecting into one side of said socket for engagement with said slotted lug, substantially as described.
2. In a burial casket provided with hinged wall portions, means for locking said wall portions in closed relation with each other, comprising a slotted lug on one of said wall portions; a socket on the other wall portion adapted to snugly receive said lug when said wall portions are in closed positions; a rearwardly yieldable stud projecting into one side of said socket for en-

gagement with said slotted lug; and a depending finger piece connected with said stud whereby the same may be manually retracted to release said lug, substantially as described.

3. In a burial casket provided with hinged wall portions, disposed at right angles to each other, means for locking said wall portions in closed relation with each other, comprising an L-shaped member secured to one of said wall portions adjacent the edge thereof, the base of said member being provided with a slot and extending perpendicularly to said wall portion; an elongated member mounted on the adjacent wall portion adjacent the edge thereof; a slotted lug projecting outwardly from one end of said elongated member and bent upwardly at one end to form an upwardly opening socket adapted to engage the base of said L-shaped member; a resilient arm secured at one end to said elongated member; and a stud projecting from said arm and adapted to engage in said slot for locking the base of said L-shaped member in said socket, substantially as described.

In testimony whereof I have signed my name to this specification in the presence of two subscribing witnesses.

FRED LUNDBERG.
